UNITED STATES PATENT OFFICE

98,055

DESIGN FOR A JAR

Benjamin F. Conner, West Hartford, Conn.

Application April 16, 1935, Serial No. 56,416

Term of patent 14 years

To all whom it may concern:

Be it known that I, Benjamin F. Conner, a citizen of the United States, residing at West Hartford, in the county of Hartford and State of Connecticut, have invented a new, original, and ornamental Design for a Jar, of which the following is a specification, reference being had to the accompanying drawing.

Of the drawing:

Fig. 1 is a plan view of a jar embodying my new design.

Fig. 2 is a side view.

The stippled and unstippled portions of the drawing are intended to represent differing colors, but not any particular colors.

I claim:

The ornamental design for a jar as shown and described.

BENJAMIN F. CONNER.
